Attorney.

UNITED STATES PATENT OFFICE.

FRANK E. WOLCOTT, OF WEST HARTFORD, CONNECTICUT, ASSIGNOR, BY MESNE ASSIGNMENTS, TO THE BEARDSLEY & WOLCOTT MFG. CO., A CORPORATION OF CONNECTICUT.

CURLING IRON.

Application filed December 16, 1927. Serial No. 240,455.

My invention relates to curling irons.

It has for its object to provide a curling iron of improved construction whereby the life of the spring, used in such an iron, is 5 lengthened. A more specific object of my invention is to provide an improved construction and one especially adapted to use in electric curling irons and including improved spacing and cooling means between 10 this spring and the iron pivot whereby breakage of the spring adjacent the pivot is overcome. These and other objects and advantages of my improved construction will, however, hereinafter more fully appear.

15 In the accompanying drawings I have shown, for purposes of illustration, one embodiment which my invention may assume in practice.

In these drawings,—

20 Figure 1 is a central longitudinal sectional view of my invention applied to an electrical curling iron, the pivoted element being shown in a plurality of positions;

25 Fig. 2 is a sectional view on line 2—2 of Fig. 1;

Fig. 3 is an enlarged longitudinal sectional view of the pivoted element without its co-operating stationary element, and

30 Fig. 4 is a sectional view on line 4—4 of Fig. 3.

In this illustrative construction I have shown a curling iron of usual construction, including an electrically heated member 1 and a usual pivoted member 2 pivoted on a 35 transverse pin 3 on a clip 4 slidable on the member 1, a plate spring 5 being disposed between the member 2 and the member 1 in a well known manner and this spring 5 herein being associated with the pin 3 in an im- 40 proved manner.

Herein, instead of having the spring 5 extend around the pin 3 in a curved portion of small radius in such manner as to bring it very close to the pin, the curved portion of 45 the spring 5 is enlarged in diameter, as at 6, and also spaced from the pin by a spacing member 7, which is of greater diameter than the pin and encircles the latter. Thus it will be noted that, since the portion 6 of the spring is disposed, and herein also supported substantially uniformly, at a greater distance 50 from the pin in such manner that the bending strain is prevented from being localized at a point substantially halfway around the curve,

as heretofore, and since the spacing member 7 55 also acts to reduce the temperature of this portion of the spring, the tendency of this spring to break at that point is substantially decreased. Further, it will be noted that I have herein made the spacing member 7 in 60 the form of a coiled spring disposed on the pin 3 between the upstanding ends or wings on the clip 4, since I find that such a spring, in addition to forming an improved spacing and cooling means for the portion 6 of the 65 plate spring 5, as heretofore described, also acts even further to reduce the temperature of this portion of the plate spring and thereby further increase the life of the same, the reduction in temperature apparently being 70 due to the convolutions of the coiled spring, which, due to their larger area and arrangement, act to dissipate the heat transmitted by the iron 1 and clip 4 to the pin 3.

As a result of my invention it is found that 75 the wearing quality of the plate spring is substantially increased. Attention is also directed to the fact that the coiled spring 7 also acts to prevent loss or displacement of the plate spring, the diameter of the additional 80 member 7 being sufficient to prevent the usual adjacent reduced portion of the plate spring from slipping past the same. Further, it will be noted that my improvement is capable of being carried out without substantially increasing the cost of the curling iron. These 85 and other advantages of my improved construction will, however, be clearly apparent to those skilled in the art.

While I have in this application specifically 90 described one embodiment which my invention may assume in practice, it will be understood that the invention is not limited thereto but may be modified and embodied in various other forms without departing from its 95 spirit or the scope of the appended claims.

What I claim as new and desire to secure by Letters Patent is:—

1. In a hair curler, cooperating curling elements having a resilient pivotal connection 100 therebetween including a pivot member and a spring having an intermediate curved portion passing around said member, and a spacing member between said portion of the spring and said pivot member.

2. In a hair curler, cooperating curling elements having a resilient pivotal connection 105 therebetween including a pivot member and

a spring having an intermediate curved portion passing around said member, and a spacing member between said portion of the spring and said pivot member, said spacing member being in the form of a sleeve.

5. In a hair curler, cooperating curling elements having a resilient pivotal connection therebetween including a pivot member and a spring having an intermediate curved portion passing around said member, and spacing and cooling means between said portion of the spring and said pivot member.

10. In a hair curler, cooperating curling elements having a resilient pivotal connection therebetween including a pivot member and a spring having an intermediate curved portion passing around said member, and spacing and cooling means between said portion of the spring and said pivot member, 20 said means being in the form of a sleeve presenting heat dissipating means.

15. In a hair curler, cooperating curling elements having a resilient pivotal connection therebetween including a pivot member and a spring having an intermediate curved portion passing around said member, and spacing and cooling means between said portion of the spring and said pivot member, said 25 means being in the form of a coiled spring encircling said pivot member.

20. An attachment for hair curlers comprising an attachment member, a pivoted curler member, a pivot member connecting said elements, a spring for said curler member having a portion enclosing said pivot member, and a spacing member between said portion and said pivot member.

25. An attachment for hair curlers comprising an attachment member, a pivoted curler member, a pivot member connecting said elements, a spring for said curler member having a portion enclosing said pivot member, and a spacing member between said portion and said pivot member, said spacing member 30 being in the form of a sleeve.

35. An attachment for hair curlers comprising an attachment member, a pivoted curler member, a pivot member connecting said elements, a spring for said curler member having a portion enclosing said pivot member, and a spacing member between said portion and said pivot member, said spacing member 40 being in the form of a sleeve.

45. An attachment for hair curlers comprising an attachment member, a pivoted curler member, a pivot member connecting said elements, a spring for said curler member having a portion enclosing said pivot member,

and a spacing member between said portion and said pivot member, said spacing member being in the form of a sleeve provided with heat dissipating means.

50. An attachment for hair curlers comprising an attachment member, a pivoted curler member, a pivot member connecting said elements, a spring for said curler member having a portion enclosing said pivot member, and a spacing member between said portion and said pivot member, said spacing member being in the form of a coiled spring encircling said pivot member.

55. In an electrical hair curler, cooperating elements including an electrically heated element and a pivoted curling element, a clip carried by the latter and receiving the former and having upturned ends and a pivot pin extending between said ends, a spacing and cooling sleeve in the form of a coiled member surrounding said pin between said ends, and a spring acting between said heated and pivoted elements and having an intermediate portion passing around said sleeve.

60. In an electrical hair curler, cooperating elements including an electrically heated element and a pivoted curling element, a clip carried by the latter and receiving the former and having upturned ends and a pivot pin extending between said ends, a coiled 70 spring forming a sleeve surrounding said pin between said ends, and a plate spring acting between said heated and pivoted elements and having an intermediate portion passing around said coiled spring.

65. In a hair curler, cooperating elements including a heated element and a pivoted curling element, a clip carried by the latter and receiving the former and having upturned ends and a pivot pin extending between said ends, a coiled spring forming a sleeve surrounding said pin between said ends, and a plate spring acting between said heated and pivoted elements having its intermediate portion passing around said coiled spring and 75 held against separation therefrom by engagement with the latter.

80. In testimony whereof I affix my signature.

FRANK E. WOLCOTT.
